Blackmore, Spenser & Flint.

UNITED STATES PATENT OFFICE.

ALBERT J. CHAMPION, OF FLINT, MICHIGAN, ASSIGNOR TO A C SPARK PLUG COMPANY, OF FLINT, MICHIGAN, A CORPORATION OF MICHIGAN.

DOUBLE-INSULATED SPARK PLUG.

Application filed November 24, 1919. Serial No. 340,102.

To all whom it may concern:

Be it known that I, ALBERT J. CHAMPION, a citizen of the United States, and a resident of Flint, county of Genesee, and State 5 of Michigan, have invented certain new and useful Improvements in Double-Insulated Spark Plugs, of which the following is a full, clear, concise, and exact description, such as will enable others skilled in the art 10 to which the invention relates to make and use the same, reference being made therein to the accompanying drawings, which form a part of this specification.

My invention relates to spark plugs designed for use with internal combustion engines to ignite the combustible mixture within the cylinder thereof; and the object of my invention is to provide a spark plug which will be more effectively insulated than 15 has heretofore commonly been the case, and a spark plug which when in use will be less liable to become short circuited than has heretofore been the case in spark plugs of the form and construction at present commonly employed and wherein the external shell or casing of the plug which carries the outer electrode is grounded upon the engine structure, and is in direct metallic contact 20 with the insulator of the plug whereby the 25 inner electrode is insulated.

My invention is shown in its preferred embodiment in the drawing accompanying and forming a part of this specification, and wherein:

35 Figure 1 is a view showing a spark plug partly in elevation and partly in section; various portions thereof being broken away in order to bring out the features of construction of the plug as a whole.

40 Figure 2 is a similar view showing a spark plug modified as to some of the elements and features thereof.

Referring now to the drawing, the reference numeral 5 designates the main insulator 45 of a spark plug, the same being made commonly of porcelain or similar vitreous material, altho my invention is in no way concerned with the particular material from which the insulator is made, and any suitable material may be employed for that 50 purpose. The insulator is provided with a longitudinally extending passage through which the inner electrode 6 of the plug extends, the upper end of said electrode being 55 electrically connected with a binding

post indicated by the reference numeral 7, in order to facilitate the connection of a conductor with the plug and through which current may be supported thereto.

Referring first to the form of my invention illustrated in Figure 1, the porcelain or equivalent insulating member 5 is itself supported by a suitable metallic supporting member 8 shown as in the form of a sleeve or bushing surrounding the same and within which the insulator is secured and whereby the same is supported. The lower end of the bushing 8 is provided with an inturned flange or ledge 9 against which a shoulder of the insulator rests, a suitable cushion being interposed between the elements referred to in order to reduce the liability of breaking the porcelain in assembling the plug. In the form of my invention illustrated the upper end 10 of the bushing 8 is turned inward and over a shoulder 11 formed upon the insulating member to thereby permanently secure the insulator in place within the metallic sleeve or bushing whereby it is supported, a suitable cushion being interposed between the parts to prevent the breaking of the porcelain. The cushions here referred to may be made of various materials, altho I prefer to form them from asbestos, or asbestos enclosed in a thin sheet copper covering as in the case of the usual yieldable metallic faced gaskets commonly used in and about internal combustion engines. It will be appreciated, however, that the porcelain or equivalent insulator need not be permanently secured in place within the sleeve or bushing which supports it, but on the contrary may be held in place by a gland nut similar to the nut hereinafter referred to to secure the bushing within the shell or casing of the 95 plug, or otherwise, should such a construction or constructions be deemed necessary or desirable.

The sleeve or bushing 8 together with the insulator supported within the same is itself supported within an external metallic shell or casing indicated as a whole by the reference numeral 12 and which carries the outer or grounded electrode 21 of the plug, said shell or casing being provided with a 100 threaded portion 13 at its lower end in order that it may be screwed into an opening provided in the cylinder of the engine with which the plug is used; while the upper end of said casing or equivalent sup- 110

port is provided with a recess 14 shown as conical in form to conform with the conical outer surface of the bushing 8 above referred to. The bushing, together with the 5 insulating member carried by it, may be secured in place within the conical recess in any way as, for example, by means of a gland nut 15 in threaded engagement with a threaded upper portion of the casing 12; 10 and suitable insulating material indicated by the reference numerals 16, 17 is interposed between the conical peripheral surface of the bushing 8 and the internal wall of the recess 14, and between a shoulder at 15 the upper end of said bushing and an inwardly extending ledge 18 of the gland nut 15; thus providing double insulation, that is, insulation due to the porcelain or equivalent material of the main insulator 5 and 20 due to the insulating material 16, 17, between the inner insulated electrode 6 and the outer grounded electrode 21 of the plug. The insulating members 16, 17 may be of various materials, among which may be 25 mentioned mica, asbestos and similar materials, to provide an effective insulation for the shell or bushing 8 and insulate the same from the external metallic casing or shell 12 of the plug.

30 The conical metallic sleeve or bushing 8 is preferably somewhat shorter than the conical recess 14 in the shell 12 within which it fits, in order to thereby provide an annular gas pocket 19 within the external shell 35 or casing, and surrounding the lower end of the insulating member 5. When the plug is in use inert burned gases occupy the space provided by the annular pocket 19 and the annular space 20 below it and between the 40 lower end of the insulator and the lower end of the casing and act to prevent the deposit of soot about the insulating member of the plug and between the same and the external metallic casing thereof, and 45 the construction in question increases to an excessive degree the length of the path over which current must travel before the plug can become short circuited. The lower or inner end of the casing is shown as provided with a separate and independent electrode 21 the end of which is located close to the inner electrode 6, altho the formation of the inner electrode and of the lower end of the shell may be such that the sparks 50 produced jump from it directly to the outer casing or to a portion thereof; and it will be appreciated that the outer electrode is grounded upon the engine because of its connection with the external metallic casing 55 of the plug.

Heretofore in spark plugs the insulating member corresponding with the insulator 5 whereby the inner electrode is carried has commonly been supported by a metallic shell which is itself in direct contact with

and is grounded upon the engine when the plug is in use; thus providing a single insulation only between the said electrode and the ground provided by the engine structure. In such plugs, and because of the 70 fact that the di-electric strength of the insulating member commonly decreases as the temperature to which the plug is subjected increases, the resistance decreases rapidly upon a rise in temperature and they tend 75 to become short circuited when they have been heated to any considerable degree, because of the reduction in resistance of the insulating member due to the heating there- 80 of. In my invention, however, the support whereby the insulator is supported is itself insulated from the engine by the layer of insulation shown at 16, from which it follows that a double insulation of the inner 85 from the grounded electrode and of the plug 90 as a whole is secured. Furthermore, the insulating material 16, as well as the joint between the insulator 5 and the sleeve 8 are protected from the effects of the heated gas 95 within the cylinder by the dead gas pocket 90 19 and the annular gas space 20 below the same and surrounding the lower end of the insulator 5, thereby keeping the said insulation comparatively cool. At the same time the insulation in question may be made up 100 of layers of mica or equivalent insulating material, which material cannot, however, be as readily used in the manufacture of the main insulator 5 of the plug; thereby providing a plug in which not only is a double 105 insulation secured, but a plug in which the two insulating members may be so selected and made of such materials as to secure a substantially constant and uniform resistance to short-circuiting when the plug is in 110 use; as it is feasible to make at least one of said insulating materials of a substance which will be affected to a minimum extent by the rise of temperature incident to the use of the plug.

In the form of my invention illustrated in Figure 2 the inner electrode 22 and the main insulator 23 are substantially the same as in the form of my invention illustrated in Figure 1, although the remaining portions of the plug differ somewhat from the forms of corresponding elements present in the plug first herein described. In this modified form of my invention the metallic supporting sleeve 24 may be made from a 115 piece of tubing the ends of which are turned inward at 25 to thereby hold the main insulator 23 in place; and said sleeve, together with the inner insulator and electrode, are held in place within a cylindrical 120 recess 26 provided in the external metallic casing 27 of the plug by forcing a flange 125 at the upper end thereof inward, as shown at 28, thus providing a unitary or one piece plug. The sleeve 24 is insulated from the 130

- external casing 27 which carries the outer grounded electrode 29 by second insulating members 30, thus providing double insulation between the two electrodes of the plug; and an annular space 31 is provided between the supporting sleeve and the outer casing which space, however, may be occupied by insulating material, if deemed preferable or desirable.
- Having thus described and explained my invention, I claim and desire to secure by Letters Patent:
1. In a spark plug, a central electrode; an external metallic shell or casing; a grounded electrode carried by said shell; double insulation interposed between said inner electrode and said outer shell or casing; and a metallic sleeve interposed between two portions of said double insulation and located out of the path of the flow of current between said central and grounded electrodes, and which sleeve serves to support said inner electrode and insulation surrounding the same.
  2. In a spark plug, a central insulator; an electrode carried by said insulator; a metallic sleeve or bushing whereby said insulator is supported; an external metallic shell or casing whereby said bushing is supported; an electrode carried by said external shell or casing; and an insulating material interposed between said external casing and said bushing, said metallic sleeve and said external shell being independent of one another and each performing its supporting function independently of the other.
  3. In a spark plug, an external metallic shell or casing having a recess formed within its upper portion; a metallic sleeve or bushing held in place within said recess, and which bushing is of less length than said recess so as to provide an annular gas pocket within said casing and between said bushing and said casing; insulating material interposed between said casing and said bushing; an insulator located within said sleeve or bushing and held in place within the same; and an electrode carried by said insulator.
  4. In a spark plug, an external metallic shell or casing having a threaded lower portion, and a conical recess formed within its upper portion; a metallic sleeve or bushing conical in form and detachably held in place within the conical recess aforesaid, and which bushing is of less length than said recess so as to provide an annular gas pocket within said casing and between the inner end of said bushing and the lower end of said recess; insulating material interposed between the interior conical wall of said casing and said bushing; an insulator located within said sleeve or bushing and permanently held in place within the same; and an electrode carried by said insulator.

In testimony whereof I affix my signature.

ALBERT J. CHAMPION.
